Application April 13, 1948, Serial No. 20,733

7 Claims. (Cl. 154—95)

1

This invention relates to the art of making signs and sign elements of that present day popularly used reflective material which is available in comparatively thin and flexible sheet form and constructed so that a multiplicity of minute glass or similar bead-like reflective particles on the display face thereof will glow as though illuminated from within or behind under the influence of light beams particularly at night. Such light beams may be directed from motor vehicle head lights.

In making display signs of sign elements or characters cut or otherwise made from the aforesaid thin and flexible reflective material, particularly in the case of large sign characters, much difficulty is experienced in the handling of the sign characters when setting and arranging them in properly aligned and squared relation to one another. Sign characters of this material require the use of a particularly quick-acting and highly tenacious adhesive substance in order to become permanently fixed to the surface on which the sign is to be made. Due to the extremely thin and flimsy nature of the sign characters formed of this material and the fact that such characters will not retain intended form while being handled and that the particular adhesive, necessarily employed, will stick fast immediately after it comes into contact with the opposed surface of the sign support and the sign characters, said characters once applied, cannot be shifted or moved without likelihood of being wrinkled, deformed or otherwise impaired. It is therefore apparent that an accurate assembly of these sign characters to a given pattern is a tedious and difficult operation often resulting in much waste of the material and the expenditure of considerable time and effort.

It is the primary object of this invention to provide improved signs of the aforesaid reflective material and novel methods of making and applying the same wherein the sign characters are formed retaining and can be readily handled without deformation or impairment and may be applied to a sign supporting surface with comparative ease and with assurance that the characters will be properly presented, aligned and squared in consideration of related sign characters and to the end that all of the difficulties and objections heretofore encountered will be eliminated.

Another object is to provide a preformed sign unit of the character described in which a supporting or carrier element forming a part thereof and lending thereto the desired rigidity and form retaining qualities serves also as a protective

2

covering for the display surface and is subject to ready removal after the sign element is cemented in place without moving, disturbing or impairing the sign element in any manner.

Another object is to provide a preformed sign element of the character described wherein opposite faces of a piece of the aforesaid reflective material forming a given sign character have applied thereon coatings of adhesive substances of differing degrees of tenacity such that the carrier element covering the reflective face of the sign element is adhered thereto by means of the adhesive having the lesser tenacity. With this arrangement upon adhering the reflective sign element to a surface for supporting it by means of the adhesive having the greater tenacity, the carrier element may be readily lifted therefrom without requiring moistening or other preparation and without disengaging, moving or disturbing the applied sign element in any manner.

Another object is to provide a preformed sign unit such as described in which the highly tenacious adhesive substance thereon for fixing the reflective sign character in place is protected until ready for use by means of a comparatively thin cover piece adhered thereto so as to be subject to ready removal whereby with the relatively stiff carrier element adhered to the display face of said sign character, the unit may be handled, packed and shipped without damage.

A further object of this invention is to provide a preformed complete sign which is made up of a plurality of characters of the aforesaid reflective material disposed between a flexible masking sheet and a flexible carrier sheet in such manner that the unit may be rolled up for storage or shipment and handled without damage, subject however to an accurate application as a complete sign in a particularly efficacious manner to a surface on which the sign is to be displayed.

A further object is to provide a novel and efficacious method of applying a made-up sign of the character noted to a sign supporting surface.

Another object is to provide a preformed complete sign unit such as described wherein the masking sheet and the carrier sheet between which the several sign characters of the aforesaid reflective material are maintained in a predetermined complete sign pattern, are so constructed and arranged that the sign characters may be readily affixed while held by such sheets in given pattern, to the surface on which the

sign is to be displayed, with said sheets adapted to be readily removed without disturbing the applied sign characters.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a top plan view of a piece of composite sheet stock from which are made sign character units embodying the present invention;

Fig. 2 is a perspective view on an enlarged scale of a sign unit embodying the present invention and which has been cut from the stock material shown in Fig. 1;

Fig. 3 is a fragmentary sectional view taken on the line 3—3 of Fig. 1 also on the line 3—3 of Fig. 2 showing the layers of the sheet material and the adhesive layers or coatings employed in the making of the stock material and sign character units respectively shown in Figs. 1 and 3;

Fig. 4 is a perspective view of the sign character unit with the protective back cover element removed to prepare the unit for application;

Fig. 5 is a fragmentary perspective view showing how the unit may be applied to the surface of a sign support and how the carrier element is removed after the reflective sign character is adhered to the sign support;

Fig. 6 is a top plan view showing how a plurality of reflective sign characters may be applied and adhered to a carrier sheet in the first step of my improved method of making a complete sign unit;

Fig. 7 is a top plan view showing how a masking sheet is applied to the reflective characters and carrier sheet in the second step of the method of making a complete sign;

Fig. 8 is a side view of the complete sign unit as when attached to a sign support on which the reflective sign characters of the unit are to be adhered, with the unit swung upwardly so that a rubber cement coating may be applied to the sign unit area of the support;

Fig. 9 is a fragmentary front elevational view showing how the complete sign unit is swung back against the support after the operation indicated in Fig. 8 is completed, to adhere the masking sheet to the support;

Fig. 10 is a sectional view taken on the line 10—10 of Fig. 9 on an enlarged scale;

Fig. 11 is a fragmentary sectional view showing how the carrier sheet with the reflective sign characters thereon is separated from the masking sheet and lifted up to make possible the application of an adhesive substance to the sign support surfaces which are exposed through stencil openings in the masking sheet;

Fig. 12 is a side elevational view showing how the carrier sheet with the reflective sign characters thereon is swung down against the masking sheet to adhere the sign characters to the adhesive coated surfaces of the sign support after the operation indicated in Fig. 11 is completed;

Fig. 13 is a fragmentary perspective view showing how the masking sheet and the carrier sheet are removed after the sign characters are adhered to the sign support;

Fig. 14 is a perspective view of typical core pieces cut out in making the stencil openings in the masking sheet;

Fig. 15 is a sectional view taken on the plane of line 15—15 of Fig. 6 with the make-up board

or table omitted and showing how the core piece for sign character A is fitted thereto; and

Fig. 16 is a sectional view in perspective of an enlarged fragmentary portion of the reflective sign character as seen from the front thereof.

It should be noted that since the introduction on the market of a certain reflective material which is produced in comparatively thin sheets, the use of this material in making signs particularly signs on motor vehicles and along streets and highways, has become singularly popular due to the fact that such material has greater durability than paints and like coatings, is obtainable in various colors and will glow as though illuminated from behind or within under the influence of light beams directed thereon, for example, as from the head lights of motor vehicles, although, light from other sources when the signs are viewed from certain angles will also cause the signs to glow. Moreover this material in being extremely thin appears as though painted on and lies as close to the supporting surface therefor as though painted thereon. The reflective quality of this material is brought about by the presence on the display surface of the material of a multiplicity of minute bead-like particles of glass or the like arranged in closely spaced relation to one another and by reason of other factors embodied in the construction and formation of the material, it being deemed unnecessary to further describe the material as it is available on the open market and its qualities are well known.

In accordance with one embodiment of this invention, letters, numerals or other sign characters are formed from laminated sheet stock designated S which, as shown in Figs. 1 and 3, consists of a cardboard or stiff paper carrier sheet 14 laid upon a sheet 15 of the aforesaid reflective material which latter overlies a sheet 16 of cellophane or like extremely thin plastic material. The reflective surface 15' of the sheet 15 and the opposed surface of the cardboard sheet 14 have applied thereon coatings 17 of rubber cement to adhere the said sheets to one another. On the back of the reflective sheet 15 is a coating 18 of an adhesive substance of greater tenacity than the rubber cement coatings and which is covered by the sheet 16. The sheets 14, 15 and 16 being of the same dimensions except as to thickness are adhered to one another as indicated in Fig. 3 and are then ready to have the sign characters cut therefrom. The dotted lines showing 19 in Fig. 1 indicate how various sign characters may be cut from the laminated stock material. The opening 20 in the stock material as shown in Fig. 1 indicates that the sign character unit letter D shown in Fig. 2 has been cut therefrom. This sign character unit designated A is shown greatly enlarged in Fig. 2 and consists of identically shaped portions of the three sheets 14, 15 and 16 superimposed in marginal alignment and which are also designated by the reference characters 14, 15 and 16 to avoid confusion. Thus the cardboard portion is the carrier element 14 for the reflective sign character 15 while the portion of the cellophane sheet is the protective cover element 16.

The cardboard carrier element 14 reinforces and facilitates safe handling and accurate application of the reflective sign character 15 to any sign displaying or supporting surface and in addition protects the reflective or display face 15' of said character so that the latter may be

packed and shipped without likelihood of being damaged.

As here shown the sheet 15 of reflective material making up the stock S has the coating 18 of highly tenacious adhesive applied thereto and covered by the cellophane or other thin plastic protective sheet 16 before the cardboard carrier sheet 14 is adhered to the reflective face of the reflective sheet 15. This cellophane or other plastic sheet 16 is treated so that when dry will adhere to and protect adhesive coating 18 but when moistened will be released and can be readily pulled free of the adhesive coating.

Fig. 4 shows how the sign character unit A is prepared for use, the cellophane cover element 16 having been removed to expose the adhesive coating 18 on the back of the sign character 15. After this the reflective sign character 15 may be applied as shown in Fig. 5 while the cardboard carrier element 14 is adhered thereto, to a sign supporting means such as the member B, the highly tenacious adhesive 18 on the back of the sign character 15 having the quality of sticking fast immediately after it contacts the surface of member B on which the sign is to be displayed. Pressure is now applied to the unit by means of a roller or other device not shown to cause an even and effective adherence of the sign character and thereafter the cardboard carrier element 14 is lifted free of the sign character 15. Due to the fact that the adhesive 18 has greater tenacity than the rubber cement it is apparent that the carrier element 14 may readily be lifted from the sign character 15 without shifting, or disturbing the latter in any manner. In this manner, letters, numerals or other sign characters may in the composite form shown in Figs. 2 and 3 safely be handled with ease and accurately applied to a sign surface in a particularly efficacious manner which would not be possible without the cardboard or like carrier elements of my invention and the manner in which they are associated with the sign characters.

It should be noted that in some instances the sheet 15 of reflective material without the coating 18 and cellophane sheet 16 thereon may be adhered to the cardboard sheet 14 by means of the rubber cement coating to form the laminated stock material from which sign character units may be cut. In such case the sign units consisting of just the sign characters of reflective material and the cardboard carrier elements will be handled in the same manner as previously described, the highly tenacious adhesive being applied before the unit is to be applied to a sign supporting surface. Once this sign character is adhered, the cardboard may be readily removed in the same manner as previously described without disturbing the sign character. The only difference between this form of my invention and the form previously described is that the first form has the adhesive of greater tenacity applied and covered with cellophane before the characters are cut from the laminated stock material whereas in this form the adhesive is applied after the cut out sign unit is ready for use, it being noted that the ultimate results are the same.

Another embodiment of this invention as shown in Figs. 6 to 15 inclusive, relates to the preparation and application of complete preformed signs made up of a plurality of reflective sign characters 22 cut from sheets of the aforesaid reflective material and held in a given pattern

ready for application to a sign support, such as the one C, shown in Figs. 8 to 13 inclusive, by means of a paper or like carrier sheet 23 and a similar masking sheet 24.

One practicable method of producing this preformed complete sign is as follows:

The sign characters 22 of reflective material each having a coating of rubber cement indicated at 25 on the reflective faces thereof are laid face up in a predetermined sign pattern on a forming board or table D as shown in Fig. 6. It should be noted at this point that the masking sheet 24 is made like a stencil with openings 26 thereon corresponding in shape to the letters or characters 22, it being preferable that the same dies employed for cutting the sign characters 22 be used for making the stencil cuts or openings 26 in the masking sheet. In making these stencil cuts in the masking sheet 24 to correspond to certain sign characters, pieces of the masking sheet are detached or cut free of the sheet as for example the triangular core or center portions of the stencil cut representing the letter A, also the core portion of the cut representing the letter B, which core portions are designated 28.

After the sign characters 22 are placed in proper order on the board or table D the separated core pieces cut out in making the stencil-like mask sheet 24 such as the pieces 28, having rubber cement coatings on both faces thereof are fitted in proper place in the characters 22.

The rubber cement may be applied in any manner to the display faces of the sign characters 22 and to both faces of the core pieces which are fitted in the said characters, provided the rear faces or backs of the sign characters 22 remain uncoated with the rubber cement.

Next the carrier sheet 23 is applied preferably by a rolling-on operation as indicated in Fig. 6, to overlie the sign characters 22, the surface of said carrier sheet opposite said characters having a coating 29 of rubber cement thereon whereby the characters 22 and the core pieces 28 will be adhered to the carrier sheet. After applying pressure as by means of a roller or the like not shown, the characters 22 and the core pieces 28 become adhered to the carrier sheet 23. Next the carrier sheet is lifted and turned over to present the characters on the then upper side of the carrier sheet with the backs of the characters exposed as shown in Fig. 7 so that the masking sheet 24 may be applied in the same manner as the carrier sheet. The masking sheet formed with stencil openings 26 corresponding in shape to the sign characters 22, has applied thereto a rubber cement coating 30 which coats with the rubber cement coating 29 on the then exposed face of the carrier sheet so that when the masking sheet is fitted over the characters 22 as indicated in Fig. 7 it will be adhered to the carrier sheet but will not be adhered to the characters 22 which are free from cement coatings on their backs and lie free within the stencil openings 26.

After applying pressure as by means of a roller not shown, to the masking sheet to effect proper adherence thereof to the carrier sheet, the sign unit is complete and appears as shown in Figs. 8 and 9 and may be rolled up or handled as a sheet or packed or stored in roll or sheet form until ready for use or it may be immediately applied to transfer the desired sign to a selected sign supporting surface.

The present invention also includes a novel

method of applying the aforesaid complete sign unit wherein the first step as shown in Fig. 8 requires that the unit be hinged as by means of a strip of adhesive tape 33 to a support or member C on the surface of which the sign characters 22 are to be applied, with the masking sheet 24 opposite said surface.

Next, the sign unit is lifted up as shown in Fig. 8 and so held in any suitable manner so that the surface of the sign support C thereunder may have a coating of rubber cement applied over the sign unit area thereof after which the sign unit is swung back to lie against said coated surface as shown in Fig. 9. The exposed surface of the masking sheet is either covered with rubber cement before the masking sheet is applied as shown in Fig. 7 or while this surface is exposed as shown in Fig. 8 and in either case the sheet will become adhered to the rubber cement coated surface of the sign support C when the unit is swung down and pressed against the sign support as shown in Fig. 9. This causes the masking sheet to firmly adhere to the sign supporting surface.

Next the carrier sheet 23 with the sign characters 22 thereon are separated from the masking sheet 24 and swung upward as shown in Fig. 11. It should here be noted that fresh rubber cement has greater tenacity than rubber cement which has been previously applied and allowed to stand for a while. Therefore as the cement on the sign supporting member C is fresh whereas the cement holding the masking sheets to the carrier sheet is older, the separation of the carrier sheet from the masking sheet may be effected without lifting or disturbing the latter. For the same reason the stencil cores 28 will stick to the fresh cement on the surface C remaining in proper position in the stencil openings 26 rather than remaining adhered to the carrier sheet 23, thus leaving perfect stencil formations in the mask for applying the special highly tenacious adhesive substance aforementioned to those parts of the surface of the member C which are exposed through the stencil openings 26 in the masking sheet. Next the aforesaid special adhesive having greater tenacity than the rubber cement is sprayed or otherwise applied to those parts of the member C exposed through the stencil openings 26 in the mask, after the operator rubs off from said exposed parts the rubber cement which has previously been applied to the surface of the member C.

After the highly tenacious adhesive is applied as aforesaid, the carrier sheet 23 with the sign characters 22 thereon is swung downwardly to fit the characters into the stencil openings 26 in the masking sheet 24 and adhere them to the surface of member C. Pressure is applied as by means of a roller (not shown) to assure uniform and effective adherence of the sign characters to the member C following which the carrier sheet and the masking sheet are lifted and removed as indicated in Fig. 13, thereby leaving the sign characters attached to the member C. The core pieces 28 will remain in the sign characters but may be readily lifted out with the fingers or by means of a suitable instrument. In this connection it should be noted that if desired the cores 28, if made of the aforesaid reflective material having a different color than the characters 22, can be adhered by suitable cement to the member C thus producing a fanciful color arrangement in the sign.

It should be noted that while this invention

deals primarily with signs made of the aforesaid reflective material it may be carried out to advantage in the manner hereinbefore pointed out with any other sheet material which has properties corresponding to those of the reflective sheet material except as to being reflective.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

1. In a preformed sign unit, a reflective sign character made of comparatively thin and flexible sheet material and having on one side thereof a reflective display surface and having a strong adhesive on the other side thereof, said character being provided on said display surface with a coating of an adhesive which requires contact with a like coating in order that two parts coated with such adhesive be removably adhered to one another, a carrier element for reinforcing and facilitating the handling of said character having thereon a coating of the same adhesive substance as on the sign character removably adhering said element and said character to one another, and a protective covering sheet adhered to the strong adhesive on the sign character adapted to be stripped free from said sign character without detaching or otherwise disturbing the latter; said sign character, carrier element, and protective covering sheet being identically shaped and superimposed in marginal alignment with each other.

2. In a preformed sign unit, a sign character made of thin and flexible sheet material and having a reflective display surface on one side thereof, there being a coating of rubber cement on the display surface side of said character and a coating on the other side of said character of an adhesive substance having greater tenacity than said rubber cement coating and the quality of adhering fast to the sign-supporting surface to which the sign character is to be adhered, and a carrier element for reinforcing and facilitating the handling of said sign character having a coating of rubber cement on one side thereof contacting the rubber cement coating on said sign character and adhering the character and the carrier element to one another; the relative tenacity of the rubber cement and said adhesive substance being such that once the character with the carrier element thereon is adhered to said sign surface by means of said adhesive substance, the carrier element may be removed therefrom without disturbing said sign character.

3. In a preformed sign, a flexible carrier sheet, a plurality of sign characters having backs and display surfaces with the latter removably adhered to one side of said carrier sheet in a predetermined sign pattern by means of coatings of like adhesive, and a flexible masking sheet removably adhered by means of coatings of like adhesive to said carrier sheet and having stencil openings thereon corresponding to the formation of said sign characters and the sign pattern formed thereby, with said sign characters nested in said openings so that the backs thereof are exposed for adherence to a sign-supporting surface on which the complete sign is to be displayed, the tenacity of the adhesive employed to adhere the sign characters to said carrier

sheet and to adhere the carrier and masking sheets together being such that when the backs of the sign characters are adhered to the said sign-supporting surface by means of an adhesive substance having greater tenacity, the carrier sheet and said masking sheet may be removed so as to leave the characters adhered to said sign supporting surface.

4. In a preformed sign unit ready for application to a sign displaying surface, a plurality of sign characters having frontal display surfaces and adhesive coating on the back faces thereof, a carrier sheet to which said characters are removably adhered by means of applications of rubber cement of less tenacity than the adhesive on said back faces and made alike to the display surfaces of said characters and to one surface of said carrier sheet, and a stencil sheet removably adhered to the other surface of said carrier sheet by means of coating applications of rubber cement and in such manner that the backs of said characters are fully exposed in the stencil openings in said stencil sheet with said characters separable from said carrier sheet through said stencil openings after the characters have been adhered to a sign displaying surface by means of the adhesive on said back faces.

5. The method of making display signs wherein such signs are made up of a plurality of separate sign characters formed of pieces of extremely thin and flexible material and have reflective frontal display surfaces, which method consists in arranging a plurality of the aforesaid sign characters in a given sign pattern, adhering said characters to a carrier sheet so that they will be removably held thereon by means of applications of rubber cement on the display faces of said characters and on one surface of said sheet respectively; and then removably adhering by means of coating coatings of rubber cement, the other surface of carrier sheet to a stencil sheet in such manner that said sheets and characters become a portable unit with the backs of said characters being fully exposed in said stencil openings and said characters being subject to removal from said carrier sheet through said openings, then adhering said characters to a sign displaying surface by means of an adhesive substance having greater tenacity than the rubber cement which adheres the characters to the carrier sheet removing said carrier sheet and said stencil sheet after said characters are adhered to said sign displaying surface.

6. The method of making a display sign unit ready for application to a sign supporting surface wherein said sign is made up of separate sign characters formed of pieces of thin and flexible material having frontal display surfaces and provided on their rear faces with an adhesive coating having the quality of permanent adhesiveness immediately after application of such adhesive coated faces thereof to a sign supporting surface, which method consists in arranging a plurality of the aforesaid sign characters in a sign pattern; removably adhering said characters of said pattern to a carrier

sheet by means of applications of rubber cement made alike on the display surfaces of said characters and on one surface of said sheet respectively, then removably adhering a stencil sheet by means of coatings of rubber cement to the other surfaces of said carrier sheet, with the rear faces of said characters fully exposed in the stencil openings of the stencil sheet for application to a surface for displaying the sign characters.

7. The method of applying a completed sign unit to a sign supporting surface wherein said sign unit consists of a series of sign characters arranged in a predetermined sign pattern and removably held by an adhesive substance on a carrier sheet and wherein a stencil sheet is removably adhered to said carrier sheet with the sign characters disposed in the stencil opening and the backs of said sign characters exposed for application to a sign supporting surface on which the characters are to be permanently affixed; which method consists in hinging the sign unit to the sign supporting surface on which the sign characters are to be displayed, by means of a piece of flexible adhesive tape applied along the top edge of the sign unit and to said surface respectively, then lifting the complete sign unit upwardly away from said surface and applying to the sign unit area of the sign supporting surface and to the exposed surface of the stencil sheet like rubber cement coatings, then swinging the sign unit back against said surface to adhere the stencil sheet thereto, then swinging the carrier sheet together with the sign characters upwardly from said stencil sheet, then applying to said exposed portions of said surface an adhesive substance having a greater tenacity than said rubber cement coatings, then swinging the carrier sheet downwardly to apply the characters thereon against said adhesive covered surfaces exposed through said stencil openings and applying pressure to adhere the sign characters to said sign display surface, then removing said adhesive strip by which the sign unit is hinged to said surface, then removing said carrier and stencil sheet in the order named so as to leave the characters adhered to the sign displaying surface.
